UNITED STATES PATENT OFFICE.

JACOB A. HARTENSTEIN, OF PHILADELPHIA, PENNSYLVANIA, ASSIGNOR TO LIPPER MANUFACTURING COMPANY, OF PHILADELPHIA, PENNSYLVANIA, A CORPORATION OF PENNSYLVANIA.

DESIGN FOR KNITTED MILLINERY FABRIC.

45,419.

Specification for Design.

Patented Mar. 17, 1914.

Application filed December 10, 1913. Serial No. 805,856. Term of patent 3½ years.

To all whom it may concern:

Be it known that I, JACOB A. HARTENSTEIN, a citizen of the United States, residing at the city of Philadelphia, in the county of Philadelphia and State of Pennsylvania, have invented a new, original, and ornamental Design for a Knitted Millinery Fabric, of which the following is a specification, reference being had to the accompanying drawings, forming part hereof, in which—

Figure 1, is a plan view of the face of the fabric, consisting of raised narrow ribbon-like stiff loops arranged throughout the face and the loops tied by knit-chains of loopings constituting the web-like back of the fabric, the same embodying my new design. Fig. 2, is a similar view of the knit-

chain back of the fabric whereof the parallel knit-chains of loopings are tied to each other by courses of threads running cross-wise of the fabric; and Fig. 3, is a perspective view showing the top, side and end of the fabric of Fig. 1.

I claim:—

The ornamental design for a knitted millinery fabric, substantially as shown and described.

In witness whereof, I have hereunto set my signature in the presence of the two subscribing witnesses.

JACOB A. HARTENSTEIN.
